UNITED STATES PATENT OFFICE.

ANNA LABNO EJK, OF SOUTH PLAINFIELD, NEW JERSEY.

DESIGN FOR A TABLE DOILY OR THE LIKE.

Application filed May 31, 1927. Serial No. 22,229. Term of patent 14 years.

To all whom it may concern:

Be it known that I, ANNA LABNO EJK, a citizen of the United States, and a resident of South Plainfield, in the county of Middlesex and State of New Jersey, have invented a new, original, and ornamental Design for a Table Doily or the like, of which the following is a specification, reference being had to the accompanying drawing, forming a part thereof.

I claim:

The ornamental design for a table doily or the like, as shown.

ANNA LABNO EJK.
